UNITED STATES PATENT OFFICE.

WILLIAM E. BLANKENSHIP, OF CHIP, KENTUCKY.

SWITCH-LOCK.

1,281,127.

Specification of Letters Patent.

Patented Oct. 8, 1918.

Application filed October 17, 1914. Serial No. 867,156.

To all whom it may concern:

Be it known that I, WILLIAM B. BLANKENSHIP, a citizen of the United States, residing at Chip, in the county of Letcher and State of Kentucky, have invented certain new and useful Improvements in Switch-Locks, of which the following is a specification.

This invention relates to electrical switches and more particularly to an improved means for locking the same in a desired position.

The primary object of my invention resides in the provision of a novel and improved locking element securable to any of the common forms of switches and is particularly adapted for use in switches of the knife blade type.

It is well known that in use of switches which are connected in a main line that repairs become necessary to the main line feeder and it has been found expedient to provide some means for preventing the closing of a switch connected to the main line so as to prevent injury to mechanics or laborers working on the feeder, I therefore provide my invention for use in locking switches in open position, but it will be readily understood that the position in which the switch is locked has very little bearing upon my invention and that the same has only been shown as locked open for the purpose of illustrating one of its various uses.

With the above and other objects in view my invention resides preferably in the construction, combination and arrangement of parts as hereinafter set forth in the specification and illustrated in the accompanying drawing, in which:

Figure 1 is a side elevation of a switch showing my improved locking means secured thereto, the switch being shown in closed position;

Fig. 2 is an end elevation of the same;

Fig. 3 is a detail perspective view of the locking element which I provide in the preferred form of my invention; and

Fig. 4 is a detail perspective view of a catch member which is used in the preferred form of my invention.

Similar reference characters indicate similar parts throughout the various views of the drawings.

Referring more particularly to the drawing in which the preferred embodiment of

my invention is illustrated, the numeral 1 indicates the base of a switch board or the like having circuit terminals 2 and 3 thereon electrically connected with the spaced apart switch terminals 4 and 5 respectively. A switch blade 6 is hingedly mounted in the circuit terminal 5 by means of the pin 7 as illustrated to advantage in Fig. 1, and said blade 6 being adapted to form an electrical circuit between the terminals 4 and 5 as illustrated to advantage in Fig. 1. As in the usual form of knife switch the terminal 5 comprises a pair of spaced apart ears 8 between which the blade 6 is disposed. The locking element which I desire to provide in this instance comprises a body portion 9 having one end thereof offset as indicated at 10 and provided with a transverse opening 11, the said member 9 being secured adjacent the pivot point 7 as indicated to advantage in Fig. 1. The upper end of the member 9 is provided with an enlarged housing portion 12 which contains a lock of any approved type. An opening 13 is provided in the enlarged portion 12 to allow of insertion of a key. One of the walls of the enlarged portion 12 which contains the lock is provided with an opening 14, the object of the same becoming apparent hereinafter. The member 9 is mounted upon the base 1 and secured to the upstanding lug 8 by means of a bolt 16, the said bolt 16 passing through a solid portion 17 disposed between the lugs 8, and having an opening 18 for the reception of the bolt 16 as indicated to advantage in Fig. 1. The bolt 16 passes through the opening 11 in the opposite portion 10 of the member 9 and is secured thereto by means of a nut 19 on the outer end of the bolt 16. The under surface of the blade 6 is rounded as shown at 20 to allow the blade to move freely.

Disposed upon the upper edge of the blade 6 and substantially intermediate its ends I provide a catch element which comprises a base 20 having a lug 21 extending upwardly therefrom, said lug 21 being provided with a catch portion 22 for reception in the opening 14 of the enlarged portion 12 of the member 9 and is adapted for engagement with the lock contained in the said enlarged portion 12. The base 20 is secured in any suitable manner to the blade 6, but I have shown openings 23 provided in the said base, said openings 23 having screws or the like 24 extending there-

through and adapted to secure the catch element to the blade 6. As shown throughout the drawings the catch element and the lock member 9 are preferably made of insulating material so as to prevent shock to a person unlocking the switch.

From the above description taken in connection with the accompanying drawings it is thought that a clear and comprehensive understanding of my invention may be had and it is thought that the advantages of the same will be readily appreciated by those skilled in the art. While the locking mechanism used with my improved switch has been illustrated as formed of some insulating material it will be readily understood that this is not an absolute necessity and that I do not desire to be limited to this particular kind of material. While I have shown and described my invention as possessing a peculiar form and construction it is desired that it be understood that I may make such changes in the detail structure thereof as do not depart from the spirit and scope of the invention as claimed.

Having thus described my invention what I claim and desire to secure by Letters Patent, is:

In a device of the class described, the combination of a base having a switch terminal thereon, said switch terminal being bifurcated to form ears, said switch terminal

having a solid lower portion, a blade pivotally mounted between said ears a locking element formed of insulating material comprising an elongated body, said body having an off-set lower end, a bolt passing through the solid portion of the switch terminal and through said lower end of said body, a nut carried upon said bolt, thus holding said body in a vertical position, said body being spaced from the rear surfaces of said terminal, owing to the off-set construction of the lower end thereof, and an enlarged housing formed upon the upper end of said body and extending beyond the front and rear sides thereof, the forward surface of said housing being in a plane in direct alinement with the portion of the off-set end which engages the solid portion of said switch terminal, the space between said off-set end and said housing permitting free movement of the blade, locking means carried within said housing and a catch carried upon said blade, whereby said catch will be held by said locking means when said blade is limited in its upward movement by engaging the forward surface of said housing.

In testimony whereof I affix my signature in presence of two witnesses.

WILLIAM B. BLANKENSHIP.
